UMBRELLA

John A. H. Siers, Jersey City, N.J.

Application January 11, 1941, Serial No. 374,037

10 Claims.

(CL 135—26)

This invention relates to umbrellas, parasols or the like and has for its primary object and purpose to provide certain improvements in an umbrella having a radially extensible and collapsible frame, and which are more particularly applicable to a frame structure of the type disclosed in Patent No. 2,047,711, issued to me on July 14, 1936.

In the patented construction the umbrella frame has telescoping rib sections to which an expansible and contractible cover sheet of elastic material is attached so that the cover sheet is stretched when the umbrella is opened to extend the frame structure and contracts without folding when the frame is collapsed and the umbrella closed. It is the primary object of my present improvements to provide a simple and efficiently operating means carried by the frame structure and coacting with a substantially inelastic cover material to automatically fold said material upon itself radially of the umbrella frame as the latter is collapsed in closing the umbrella.

More particularly, in a preferred embodiment of the invention, I pivotally attach to each inner rib section of the umbrella frame a folding member, spring pressed outwardly against the inner surface of the cover material. When the umbrella is open and the frame extended, the strain or tension on the cover material holds said folding members in substantially parallel relation to the rib sections and the spring means thereof is placed under stress. Thus, as the umbrella is closed, in the relative movement of the rib sections, said pivoted folding members are urged radially outward and against the cover material to fold the latter upon itself as the frame ribs move inwardly to the completely closed position in parallel relation with the umbrella staff.

It is a further object of the invention to provide such an automatic folding means for the inelastic cover material which will operate without puncturing or otherwise injuring the cover material and which will compactly fold the surplus material as the extensible frame collapses so that in the reduced over-all length of the closed umbrella, the cover material will not render the same unduly bulky, thus enabling the closed umbrella to be readily inserted into a case or container of minimum diameter.

With the above and other objects in view, the invention consists in the improved umbrella or parasol and in the form, construction and relative arrangement of its several parts, as will hereinafter be more fully described, illustrated

in the accompanying drawing and subsequently incorporated in the subjoined claims.

In the drawing wherein I have illustrated one simple and practical embodiment of the invention and in which similar reference characters designate corresponding parts throughout the several views:

Fig. 1 is a fragmentary side elevation, the cover material of the umbrella being shown in section and the frame structure in open or extended position.

Fig. 2 is a fragmentary perspective view showing an intermediate position of the umbrella frame and cover folding means.

Fig. 3 is a side elevation with the cover material shown in section of the completely closed and collapsed umbrella.

Fig. 4 is an enlarged top plan view of one of the inner rib sections and the folding member mounted thereon.

Fig. 5 is a side elevation thereof.

Fig. 6 is a detail transverse section on an enlarged scale taken on the line 6—6 of Fig. 5, and

Fig. 7 is a similar sectional view taken on the line 7—7 of Fig. 5.

Referring in detail to the drawing, in which I have illustrated a collapsible umbrella staff and frame structure and which is, in all material respects, substantially the same as that shown in the issued patent above identified, 5 and 6 respectively indicate the two collapsible staff sections of thin walled metal tubing, the lower section 6 being preferably telescoped within the upper section 5. The lower end of the staff section 6 is provided with a handle member 1 of any desired ornamental form, and suitable latch means is provided, as in said issued patent, for releasably retaining said staff sections in extended or telescoped relation.

To the upper end of the staff section 5, the inner rib sections 8 are pivotally attached at one of their ends in any approved manner as indicated at 9. These rib sections may be of channel shape in cross section as in said patented construction, and are formed from light sheet metal strip, preferably aluminum. Within each of these rib sections 8, an outer longitudinally slideable rib section 10 is engaged. To the inner end of each of these rib sections 10, the outer end of a main stretcher rod 11 is pivotally connected. The inner ends of these stretcher rods are pivoted to one end of the runner 12 which is slidably engaged on the staff section 5. This runner carries a suitable latching lever 13 to retain said

runner in its extended position on the staff section when the umbrella is open.

To each of the rods 11 intermediate of its ends, one end of an auxiliary stretcher link 14 is pivotally connected as at 15, the other end of said link being pivotally attached as at 16 to staff section 5, in inwardly spaced relation from the pivoted ends 9 of the rib sections 8.

The cover material for the frame, indicated at 17, is of silk, cotton or other substantially inelastic material and is centrally attached in any suitable manner to the end of the staff section 5. This cover sheet is of such diameter that when the umbrella is opened and the rib sections 10 extended with respect to the rib sections 8, as seen in Fig. 1, said cover material is under more or less tension and smoothly overlies the frame structure, the outer edge of said cover sheet being attached in any approved manner to the outer ends of the rib sections 10. The said cover sheet is otherwise unattached to the relatively movable rib sections 8 and 10.

To each of the rib sections 8 in suitably spaced relation from its pivoted end 9, a sheet metal bracket element 18 is fixedly secured. This bracket element at one of its ends is provided at opposite sides of the rib 8 with the outwardly projecting ears 19 in which the ends of the pin 20 are fixed. To this pin one end of the cover folding member 21 is pivotally connected. This member is of channel cross sectional form, and as shown in Figs. 6 and 7, the channel thereof opens outwardly in opposed relation to the cover sheet 17 so that the opposite edge or side walls of said channel member will have sliding bearing contact at spaced points with the cover sheet. A coiled spring 22 on the pin 20 acts to yieldingly urge the member 21 radially outward from the rib 8 and against the inner surface of the cover sheet 17. The other or free end of the folding member 21 is preferably curved inwardly towards the rib 8 as shown at 23 so that in the folding action of said member on the cover sheet, liability of cutting or puncturing the cover material will be obviated.

The cover sheet 17 is securely attached to each of the folding members 21 at the pivoted end thereof, by means of a thread or cord indicated at 24, or by any other preferred means so that in the collapse of the umbrella frame and the movement of the members 21 with respect thereto, said cover material is folded upon itself at each of these points of attachment for a radial distance which is equivalent to the length of the members 21.

In the operation of the structure above described, when the runner 12 is moved outwardly on the staff section 5, the stretcher rods 11 slide the rib sections 10 outwardly relative to the rib sections 8 so as to distend the frame to its maximum diameter. In such operation, the cover material 17 is somewhat stretched or placed under tension, thereby holding the members 21 in close more or less parallel relationship to the rib sections 18, against the resistance of the springs 22, as seen in Fig. 1 of the drawing.

When the umbrella is closed and the runner 12 moved downwardly on the staff section 5, the rib sections 8 are drawn inwardly towards the staff and the sections 10 of each rib are also slidably moved inwardly relative to the rib sections 8. As shown in Fig. 2 of the drawing, as the umbrella frame is thus collapsed and reduced in diameter, the springs 22 act to pivotally move the members 21 outwardly on the rib sections 8,

and thus fold an intermediate section of the cover material upon the innermost portion of said cover extending between the pivoted ends of said folding members and the pivoted ends 9 of the rib sections 8. This folding action of the members 21 under the influence of the springs 22 continues until the frame structure is completely collapsed and said members extend in the opposite direction from their pivots with respect to that seen in Fig. 1 and again lie in substantially parallel relation to the folded rib sections 8, which in turn are disposed in closely adjacent substantially parallel relation with the staff section 5. In this manner, as seen in Fig. 3, the excess cover material in the collapsed condition of the frame structure is compactly folded as indicated at 25 between the members 21 and the rib sections 8. The staff section 6 is then telescoped within the section 5, thereby very materially reducing the over-all length of the umbrella when closed. By automatically and compactly folding the substantially inelastic cover material in the contraction of the frame structure, as above described, excessive bulk in the closed position of the umbrella is avoided so that after securing the pleats or folds of the cover material between the frame ribs in overlapped relation by means of the usual tie cord or tape, the closed umbrella may be easily inserted within a case or holder of minimum length and diameter.

In opening the umbrella, after the staff section 6 has been extended from the section 5, the umbrella is held in inverted position and gently shaken so that the rib sections 8 and stretcher rods 11 will swing outwardly from the staff section 5, after which the runner 12 is moved outwardly on the latter staff section to distend the collapsible frame structure and open the umbrella as above described.

From the foregoing description, considered in connection with the accompanying drawing, it is believed that the nature of my present improvements in my prior patented invention, and the operation and advantages thereof in practical use will be fully understood. It will be appreciated that by a very simple addition to the patented structure, I am enabled to employ the ordinary substantially inelastic cover materials in accordance with conventional practice in the art instead of the special cover of elastic or radially stretchable material referred to in my issued patent. At the same time, like the patented construction, the action is entirely automatic, and no additional hand manipulation of relatively movable parts is required other than the actuation of the runner 12 in opening and closing the umbrella.

I have found that a collapsible umbrella of this type with my present improvements, operates in a very positive and efficient manner, and without injury to the cover fabric so that the improved umbrella will give reliable and satisfactory service, for a period of time equal to the life of the standard umbrella.

In the foregoing description and accompanying drawing I have disclosed a practical mechanical embodiment of the invention which may be manufactured and profitably sold at a reasonable cost to the purchaser. While I have referred to my present improvements as applied to a collapsible frame structure of the type shown in my issued patent, it is nevertheless to be understood that it is possible that such improvements may also be employed with equal efficiency in con-

nection with other umbrella frame structures, and that I do not consider the present invention as necessarily limited to such specific application. Also as to the several details relative to the mounting and arrangement of the cover folding members, it is possible that changes or modifications therein may be found desirable. Accordingly, it is to be understood that I reserve the privilege of resorting to all such legitimate changes in the form, construction and relative arrangement of the several elements as may fairly be comprehended within the spirit and scope of the appended claims.

I claim:

1. In combination with an umbrella frame pivotally connected with a staff, said frame having radially extensible and collapsible ribs, a cover material on said ribs and means for opening and closing said frame; means carried by said frame and coacting with the cover material to radially fold a section thereof upon itself in the closing movement of the frame.

2. In combination with an umbrella frame pivotally connected with a staff, said frame having radially extensible and collapsible ribs, a cover material on said ribs and means for opening and closing said frame; means carried by each frame rib and movable relative thereto, coacting with a section of the cover material to fold the same upon itself in the closing movement of said frame.

3. In combination with an umbrella frame pivotally connected with a staff, said frame having radially extensible and collapsible ribs, a cover material on said ribs and means for opening and closing said frame; a folding member pivoted at one end on each rib, and spring means urging said member outwardly against the cover to automatically fold a section of the cover material upon itself in the closing movement of the frame.

4. The structure described in claim 3 in which the cover material is attached to each folding member at its pivoted end and said material moves the folding members in one direction on the ribs in the opening movement of the frame to place said spring means under stress.

5. The structure described in claim 1 in which each frame rib comprises inner and outer sections and the cover folding means is mounted on each of the inner rib sections.

6. The structure described in claim 2 in which

each frame rib comprises inner and outer relatively movable sections and the cover folding means is mounted upon one of said rib sections for movement in the plane of the rib movement.

5 7. The structure described in claim 3 in which each frame rib comprises inner and outer relatively slidable sections and said folding members are mounted on the inner rib sections.

10 8. In combination with an umbrella frame having ribs each comprising an inner section pivotally connected with a staff and an outer section slidable on said inner section, means for opening and closing said frame operatively connected with the outer rib sections to extend and retract the same relative to the inner sections; a cover of substantially inelastic material secured to the staff and to said outer rib sections, and relatively movable means on each inner rib section attached to the cover material and spring pressed against the latter to automatically fold a section of said material radially upon itself in the closing movement of the frame and the retraction of the frame ribs.

15 9. In combination with an umbrella frame pivotally connected with a staff, said frame having radially extensible and retractable ribs and means for opening and closing said frame; a substantially inelastic cover material attached to the staff and the free ends only of said ribs, a folding member for each rib and means for pivotally mounting said member at one end on the rib, connecting means between said folding members and the cover material, and means yieldingly urging said members outwardly against the cover material to fold a section of said material radially upon itself in the retraction of said ribs, and said cover material being unfolded and moving said folding members to place said yielding means under stress when the frame is 20 25 30 35 40 45 opened and said ribs extended.

10. The structure described in claim 9 in which each rib comprises an inner section pivoted to the staff and an outer section longitudinally slid able on said inner section and said opening and closing means is connected with the outer rib sections to actuate the same, and said folding members are mounted on the inner rib sections and are of approximately one-half the length of said rib sections.

JOHN A. H. SIERS.
